United States Patent Office

Des. 194,581
Patented Feb. 19, 1963

194,581

A COMBINED SHELF AND HOLDER FOR MOPS AND THE LIKE

Eldridge W. Thompson, Jr., 3212 Yanceyville Road,
Greensboro, N.C.

Filed Oct. 2, 1961, Ser. No. 66,927

Term of patent 14 years

(Cl. D9—2)

FIG. 1

FIG. 3

FIG. 1 is a front perspective view of a combined shelf and holder for mops and the like embodying my new design;

FIG. 2 is a transverse sectional view thereof taken through the approximate center of FIG. 1; and

FIG. 3 is a reduced fragmentary rear perspective view thereof.

What I claim is:

The ornamental design for a combined shelf and holder for mops and the like, as shown and described.
